COVER AND BRUSH SUPPORT FOR SHAVING BOWLS

Glenn F. Claypool, Oak Park, Ill.

Application June 26, 1939, Serial No. 281,186

2 Claims. (Cl. 45—136)

This invention relates to shaving equipment, and particularly to a bowl designed to contain shaving soap, and to be employed in the process of making a lather from such soap. The purpose of the invention is to provide, as a part of the bowl structure, a rest or support for a shaving brush so that the brush will be disposed in proper position when not in use, and will be conveniently at hand when wanted. The invention consists in certain features and elements of construction, as herein shown and described and as indicated by the claims.

In the drawing:

Fig. 1 is a side elevation of a shaving bowl and cover embodying this invention.

Fig. 2 is a top plan view of the same.

Fig. 3 is a transverse section of the cover taken substantially as indicated at line 3—3 on Fig. 2.

Fig. 4 is a partial transverse section taken as indicated at the plane of line 4—4 on Fig. 2.

Fig. 5 is a plan view on a smaller scale showing a modification of the cap.

Fig. 6 is a vertical section of the modification taken on a diametral plane.

The bowl shown at 1 in Fig. 1 is intended to contain a quantity of shaving soap fitted snugly in the bowl and designed to remain therein while in use—that is, while a brush and a limited amount of water are employed for working up a lather for use in shaving. The bowl is provided with a removable cover, 2, which, as shown, includes a skirt portion, 3, depending from the top wall, 4, and formed with interrupted threads, 5, which inter-engage with similar threads, not shown, on the inner surface of the rim of the bowl, 1.

A shaving brush used in conjunction with the bowl, 1, should be well shaken after use to remove as much moisture as possible from the bristles, and then it should be disposed in a position in which the bristles will have a chance to dry so as to avoid deterioration, which might result from leaving them in a constantly dampened condition. Brushes of this character are frequently made with a flat-ended handle, so that they may stand upright with the bristles uppermost, but this tends to allow moisture to accumulate at the base of the bristles. As indicated in dotted outline in Fig. 1, a brush of this character usually comprises the bristles at A, a central body portion, B, in which the bristles are rooted so as to extend from one end thereof, and, finally, a handle portion, C, extending from the opposite end of the body, B. If a brush of this type be

supported horizontally with its bristles extending out of contact with the support so as to leave them freely exposed to the air, it will dry effectively. Therefore, the present invention provides the cover, 2, with a special formation of its top wall, serving as a rest or cradle to support the brush horizontally, as indicated in Fig. 1. This formation comprises a pair of parallel, upwardly projecting ribs, 6, 6, which are spaced apart by a substantial distance, but something less than the usual diameter of the body portion, B, of a brush, so that they form a channel extending diametrically across the top wall of the cover, 2. The body portion, B, of the brush, which is circular in cross-section, will thus rest in the channel between the ribs, 6, 6; and to position it longitudinally in the channel and prevent it from slipping endwise therein, I prefer to form the ribs, 6, 6, with notches, 7, 7, disposed at the middle of the length of said ribs, 6, 6. As shown, these notches may be of arcuate form and in that case they are of such radius that they do not actually contact the curved body, B, throughout their length, but only at each end of the notch. Thus there are provided four points of contact for the body, B, in the upstanding ribs, 6, 6, and the brush is both supported and positioned by these four points, indicated at 7a in the drawing.

In many instances the center of gravity of the brush will be located within the body portion, B, so that the brush will rest with its axis substantially horizontal, as shown in Fig. 1; but if it should happen that the weight of the handle, C, shifts the center of gravity so that the handle end of the brush tends to tilt downward, the handle will be arrested against the cover, 2, and the brush will be only slightly inclined from the horizontal; and in any case the bristles will be supported out of contact with the adjacent surface of the cover to afford them an opportunity to dry effectively.

Figs. 5 and 6 illustrate a modified form of cap in which the support for the brush is quite different in appearance but performs substantially the same function as that of the form already described. In this design the cap is formed with a central circular embossment or table, 8, from which there project four upstanding rests or supports, 9, of approximately conical formation. As indicated in dotted lines, the body of the brush seats itself upon these projections, 9, with its axis substantially horizontal and with the bristle portion elevated out of contact with the surface of the cover, 2.

Thus the shaving soap bowl with which the brush is used provides a support on which the brush is certain to be disposed in a position which will insure its proper conditioning for further use, 5 and where it will be most conveniently at hand when again required. It will be evident that the brush supporting means may take a variety of forms, and various alterations in the construction might be made without departing from the spirit 10 and scope of the invention, and that the same is therefore not limited to the particular form herein shown and described except in so far as indicated by the appended claims.

I claim:

15 1. A cover for a shaving soap bowl adapted to support a shaving brush having a bulbous body portion, said cover having an upwardly open channel formed in its top wall, said channel being of substantial width but somewhat narrower than 20 the body portion of a shaving brush, and both walls of said channel having complementary recesses cooperating to form a cradle adapted to contact a bulging body portion of the brush at

four points for positioning it definitely on the cover with its axis approximately horizontal and with its bristles out of contact with the cover.

2. The combination of a bowl and a cover 5 threaded for inter-engagement, said cover adapted to support a shaving brush having a bulbous body portion, said cover having a pair of ribs upstanding from its top surface and spaced apart at opposite sides of the diameter of the cover, said ribs having outer faces parallel to 10 such diameter and constituting a finger grip for rotating the cover in securing it or disengaging it from the bowl, said ribs being spaced apart by less than the diameter of a shaving brush body, providing a trough for lodgment of its rounded 15 form, and having mutually opposed recesses in their inner faces which accommodate a bulging portion of the brush body and oppose its longitudinal movement on said ribs while supporting the bristles of the brush in approximately horizontal position above the adjacent surface of the cover. 20
